GOLF TEE

Robert W. Ankney, Walton Hills, Ohio

Application November 10, 1953, Serial No. 27,527

Term of patent 14 years

(Cl. D34—5)

To all whom it may concern:

Be it known that I, Robert W. Ankney, a citizen of the United States, residing at Walton Hills, in the county of Cuyahoga and State of Ohio, have invented a new, original, and ornamental Design for Golf Tee, of which the following is a specification, reference being had to the accompanying drawings, forming a part thereof.

In the drawings:

I claim:

The ornamental design for a golf tee, substantially as shown.
